SMOKING PIPE

John R. Shepard, 1511 Gregory St.,
San Diego, Calif. 92102

Filed Nov. 19, 1970, Ser. No. 26,077

Term of patent 14 years

Int. Cl. D27—02

U.S. Cl. D85—8

Fig. 1

Fig. 2

Fig. 3

Fig. 4

FIG. 1 is a perspective view of a smoking pipe, showing my new design;

FIG. 2 is a side elevational view thereof;

FIG. 3 is a top plan view thereof; and

FIG. 4 is an end elevational view as taken from the left hand end of FIG. 2.

I claim:

The ornamental design for a smoking pipe, as shown.
